UNITED STATES PATENT OFFICE.

MURDICK LYTLE, OF OIL CITY, PENNSYLVANIA.

IMPROVEMENT IN THE METHODS OF WORKING OIL-WELLS.

Specification forming part of Letters Patent No. 146,600, dated January 20, 1874; application filed December 22, 1873.

To all whom it may concern:

Be it known that I, MURDICK LYTLE, of Oil City, in the county of Venango and State of Pennsylvania, have invented a new and useful Method of Working Oil-WellS; and I do hereby declare that the following is a full, clear, and exact description thereof, reference being had to the accompanying drawings, making part of this specification, in which—

Figure 1 is a longitudinal section, showing mechanism which I employ for working a series of wells according to my new method, compressed air from a single reservoir of power being used to actuate the said mechanism. Fig. 2 is a view, showing partly in section and partly in elevation the mechanism adapted for working a series of wells, modified so as to permit of water under high pressure, and supplied from a single reservoir of power being used as the actuating agent. Fig. 3 is a perspective view, on an enlarged scale, of the engine which I use, and which is shown in Fig. 1. Fig. 4 is a modification both of the regulating device of the engine and of the mode of connecting the engine to the oil-well pump.

The nature of my invention consists in operating a series of oil-wells, which yield different quantities of oil during the same period, by a single great power, which is communicated to the respective pumps of the wells, according to the quantity of the yield of oil from the wells, in such divided quantities that the speeds of the respective pumps are controlled and only the requisite consumption of power for each well takes place.

The means which I employ for carrying out my invention consists of single-acting engines provided with a regulator on the exhaust-stroke, and with throttle-valves, and with connecting mechanism, which insures open inlet-ports on the completion of the down-stroke, or when the pistons of the engines are relieved from the force of the great power.

The utility of my invention will be seen from the following statement: It is common in the oil-regions to employ a large boiler for supplying steam to several engines of that class which have balance-wheels, and such engines when the steam gets low stop, and it is necessary to help them over the dead-center before they start again; hence, in pumping what are known as "head-wells," there is considerable

time lost in going the rounds to start each engine. My single-acting regulated engines, which are always open for a new start, obviate the difficulty and loss of time just named. Further, as experience has shown that it takes about as much steam to run a well when pumping nothing from it, as when drawing a small stream of oil—say, several barrels per day—it will be readily understood that running a twelve or sixteen horse power engine twenty-four hours, and obtaining thereby only three or four barrels of liquid, is a very unprofitable business, especially as the same power, if properly applied, would pump three or four hundred barrels in the same time.

According to the old mode of working oil-wells, it is common in some localities, where the wells are small, to use large engines, while the stream of oil or water pumped is not larger than a straw. My plan is with such wells to use an engine which makes two or three quick strokes per minute, and do the work as well as with an engine running at a speed of sixty or seventy strokes per minute; and with my plan, in those localities where it is common to drill fifty to one hundred feet below the oil-producing rock for the purpose of making pockets, the oil can be pumped from the pockets by heads as often as the pockets fill; while in those localities where it is injurious to drill below the oil-rock, the pumping can be carried on steadily and the proper yield secured, and still all the engines employed for working the pumps operated from one common great power, which power in short range of territory may be steam, and in a greater range may be compressed air or water under high pressure.

To enable others skilled in the art to make and use my invention, I will describe the same with reference to the drawings.

A B C D represent four independent single-cylinder engines open at the top, and with exhaust-passages a b c d near the upper end, as shown. These engines are provided with pistons a¹, inlet-ports a² b² c² d², and with valves a³ b³ c³ d³, and with escape-pipes a⁴ b⁴ c⁴ d⁴. These valves are connected with rods f f¹ f² f³, which move up and down with the pistons, by means of rocking arms d⁵ b⁵ c⁵ d⁵. The pistons and valve-rods are connected by cross-heads g g¹ g² g³, and these cross-heads act upon toes

or collars h h^1 of the rods in the up and down strokes. In order to accelerate the opening of the valves on the down-stroke, spiral springs m are arranged between the sliding collars h^1 and stops h^2 of the valve-rods. To insure the compression of these springs in the down-stroke, offsets n are formed on the engine-cylinders A and B, and upon these offsets the stops h^2 , or horizontal portions of bent rods o , momentarily hang on the down-stroke, and in order to throw these stops laterally off the offsets the bent rods o are arranged between the fixed collars h h^2 , and are made with an angle or bend, h^3 , so that said rods shall be struck by the cross-heads of the piston and valve-rods in the movement of the piston, and thereby be set free from the offsets n . This contact of the cross-heads with the bent rods causes the valve-rods to turn slightly, and in order to insure their return with the bent rods to a position for a repetition of the operation, spiral springs q are fitted upon the valve-rods below the stops h^2 , said springs being fastened by one end to the rocking arms a^5 b^5 of the valves, and by the other end to the valve-rods, and are kept under tension by lateral contact of the bent rods with the offsets n , and are only set free by the said rods rising higher than the offsets and moving laterally over them. E E^1 E^2 E^3 are oil-well pumps of any suitable construction, and F F^1 F^2 F^3 are regulating-pumps, which are furnished with two inlet-passages, r r^1 , one of which is closed by a valve, s , and the other by a cock, s^1 . The valves open with an upward movement of the pistons of the pumps, and close with a downward movement. The cocks are left open more or less, so as to receive with the upward movement and discharge with the downward movement of the pistons. The lower ends of the regulating-pumps are submerged in a fluid contained in vessels t . The fluid in the vessels t is continually being pumped from and back into the vessels. The fluid drawn into these auxiliary pumps serves to form water-cushions, which ease and regulate the exhaust or down stroke of the engine-pistons. G G^1 G^2 G^3 are walking-beams, to which the pistons of the engines, also of the oil and regulating pumps, are connected. These beams are connected to pillars or standards H H^1 H^2 H^3 . I is the main supply-pipe leading from a compressed-air reservoir of great power. To this pipe, by means of branches, the several engines are connected, and each engine, near the point where the power is admitted to it, is provided with a throttle-valve. These throttle-valves are lettered J J^1 J^2 J^3 .

In Fig. 4 of the drawings the piston of the engine, instead of being connected to a walking-beam, is connected direct to the sucker-rod of the oil-well.

In Fig. 2 an air chamber or vessel, V, is combined with each of the engines for a purpose which will be explained in giving the general operation of the apparatus.

It will be observed, from an inspection of

Figs. 2 and 4, that the auxiliary pump for regulating the down-stroke is not employed, its office being supplied by modified devices, which will also be referred to in giving the general operation of the apparatus.

At k k , Fig. 2, a modification of the valve shown in all the other figures is represented. This modification consists in substituting any ordinary slide-valve for the circular valve.

In describing the operation, I shall, to facilitate the description, refer to Fig. 4 first. In this plan the top of the cylinder is closed, and the down-stroke of the piston is regulated by turning the stop L. In this plan there is also a regulating device, L ^{1} L ^{2} , which will be of advantage under certain conditions. With this plan we will say piston a^1 is down—as in Fig. 1, engine A—the rocking arm a^5 down, and the valve-passage a^2 open. Now, if the pipe I is full of compressed air, and the throttle J open, the power will rush into the cylinder and cause the piston a^1 to rise and carry with it the sucker of the oil-well pump. As the piston rises the air above the piston a^1 is driven out of the cylinder through the valve L ^{2} , and the piston will immediately close the outlet a , and compress the balance of the air in chamber L ^{6} , forming thereby an air-cushion, to stop or keep the piston in proper bounds, when the exhaust is much contracted, or a rush of gas comes in the well. It should be understood that if the piston passes by the outlet a , the exhaust is opened at L ^{2} until the piston settles down and closes outlet a . When the piston gets below a , then L ^{2} closes, and the only inlet to the chamber L ^{6} is the cock L ^{1} , which becomes at this stage a means for regulating the down-stroke by producing a partial vacuum in chamber L ^{6} .

We will now turn to Fig. 1 of the drawings, and describe the operation of the valve-motion and the other parts connected. It should be understood that the valve-motion in all the figures is the same, except in two of the figures, as before mentioned, a slide-valve is substituted for the way-cocks.

In engine-cylinder A the piston a^1 and the rocking arm a^5 are down, and the inlet port a^2 open. The compressed air, entering into the cylinder, forces up the piston and the walking-beam G, and thereby raises the sucker-rod E ^{6} of the oil-well pump E, and at the same time the sucker-rod F ^{7} of the governing-pump E is raised. As this latter pump is operated, on the upstroke, fluid from the vessel t flows into the cylinder thereof at the two inlets r r^1 , but on the down-stroke the fluid which entered is expelled only through the opening r . This manner of slowly discharging the fluid from this pump insures a very slow and reliable down-stroke.

In engine-cylinder B the piston b^1 and the rocking-arm b^5 are up, and consequently the exhaust-port w is open, and the exhaust air is let out at b^4 , which is an escape without any regulating-cock, such as is shown at L in Fig. 4. In this plan the down-stroke is governed

by the auxiliary pump F¹, in substantially the same manner as shown at F in Fig. 1. The engines A and B have each an escape, as at a and b, but as the tops of the cylinders are open the air-chamber L⁶ and the valves L¹ L² are not used. When L², L¹, and L⁶ in Fig. 4 are not used, then the cylinder should be considerably higher than the regular upstroke of piston a¹. The valve a⁵ and pump E allow a variable travel at the upper stroke, even to the dispensing with vent a. These engines and the others, C D, may have the spiral springs, the bent rod, the offset, and other parts shown in Fig. 3 of the drawings, for insuring a quick opening of the inlet-port. In the operation of the regulating-pumps the water in the vessels is passed alternately in and out, and therefore will last a long time. In connection with the air or engine pipe a compressor is employed, which is of sufficient capacity to supply all the engines connected with the well with power sufficient to pump all the wells empty. In practice, those engines nearest the source of power will have to be throttled more than those at a distance from it.

I propose to proportion the speeds of the engines about as follows: Say, we have eleven oil-wells arranged as in Sheets 1 and 2 of the drawings. Engine for No. 1 may have thirty strokes per minute; No. 2, five strokes; No. 3, three strokes; No. 4, six strokes; No. 5, four strokes; No. 6, thirty strokes; No. 7, twenty-five strokes; No. 8, twenty strokes; No. 9, eighteen strokes; No. 10, fifteen strokes; No. 11, ten strokes.

In the use of water under high pressure the pipe I should be secured from frost and a force-pump substituted for the air-compressor—say, a pump similar to that now used for forcing oil through the pipe-lines—such pump forcing a thousand barrels of oil per day through twelve to fifteen miles of two-inch pipe, the pipe being subjected to a pressure of one thousand pounds to the square inch.

Referring to Fig. 2, the engines 10 and 11 will be used to explain the operation with water-pressure. Cylinder A should be small in the bore—say, to receive a two-and-a-half-inch piston, the length of the stroke the same as in the air-engines. The valve should be the same as in the air-engines, unless changed to a slide-valve. The throttle may also be the same as in the other engines. Now, to work advantageously with water, an air-vessel, V, is used between the throttle and valve-motion. This vessel is of sufficient capacity to store power for one stroke of the piston without much diminution of the pressure in itself. Say, all the engines connected with the water-pipe are provided with air-vessels and throttles, and it is desired to start the wells flowing, all that is necessary is to set the throttles in all the engines so the water will rush into vessels V through small openings until the

air in the vessels becomes of the same pressure as the water in the engine-pipe I. Next, regulate the exhaust so that the down-stroke will be very slow. Now, if the piston in engine 11 is down, the valve a³ open, then the water in the air-vessel will rush into the engine-cylinder and make the upstroke. All this time the water is still flowing through the throttle-passage, but not fast enough to keep the pressure in vessel V from being considerably lessened during the upstroke of the piston. When the upstroke is finished, or the piston is coming down slowly, water will be rushing into vessel V for the next stroke. This plan of storing power in the air-vessels allows the supply-pipe to be reduced in size. Say, there is a well twelve thousand feet from any other well, and it will produce one or two barrels per day. One-half-inch pipe from the main might be laid to reach it, and the air-vessel depended upon for accumulating power during the down-stroke to make the upstroke.

In all of the single-cylinder engines which I employ the weight of the parts is sufficient to insure the down-stroke of the piston, and to have this stroke regular is very important.

I would state that, in practice, the engines may or may not have walking-beams. The use of the beams is resorted to only in such localities as it may be found advantageous to use them. It is found that in working a large oil-field with engines all taking power from the same source, and some of the wells in a valley and some on top of a hill, the depths will vary from three to five hundred feet—those in a valley, say, five hundred feet deep, and those on the hill one thousand feet deep. This renders it important that the several engines should be proportioned to the work to be done. Now, in order to make the same engine answer for duty on high or low ground, the walking-beam is used and the well-pump connected on the beam at such point as will allow the engine to work advantageously. An engine for two-foot stroke in a five-hundred-foot well would require a beam for a thousand-foot well, and the pump would be placed half-way between the engine and fulcrum of the beam.

What I claim as my invention, and desire to secure by Letters Patent, is—

The method, substantially as herein described, of operating a series of oil-wells which yield different quantities in a given period, said method consisting in the employment of a series of single-acting engines with the exhaust-stroke regulated to give the proper number of strokes to each engine according to the yield of oil from the wells being pumped, substantially as and for the purpose set forth.

MURDICK LYTLE.
